[57] CLAIM

The ornamental design for a combined fishing rod rack and carrier, substantially as shown and described.

DESCRIPTION

FIG. 1 is a front perspective view of a combined fishing rod rack and carrier showing our new design;

FIG. 2 is a rear perspective view thereof;

FIG. 3 is a top plan view thereof; and

FIG. 4 is a right side view thereof.

The left side of the combined fishing rod rack and carrier is a substantial mirror image of the right side.
